UNITED STATES PATENT OFFICE

BENJAMIN W. KLEIN, OF NEW YORK, N. Y.

HEEL LIFT

Application filed April 9, 1930. Serial No. 442,727.

This invention relates to heel lifts, and more particularly to a shoe heel lift of rubber or other resiliently yieldable cushioning material such as is commonly employed as the top lift of the shoe heel for sound deadening purposes and to relieve the body of the wearer of shock or jar in walking.

It is an object of the present invention to provide a heel which produces cushioning effects of a distinctly novel type in this art. I have found that by forming the bottom surface of the rubber heel with a cavity, that extends almost to the opposite or "lift" face of the heel, so that a very thin wall between the cavity bottom and lift face is formed, and, at the same time, enclosing the lift face with a lip or rand, so that it is spaced from the lift of the shoe when the heel is attached thereto, and also forming a projecting portion which extends from its point of attachment with the said thin wall to a point beyond the bottom surface of the heel, the heel will function with a cushioning action created by the above noted features, to provide a much more yielding or soft engagement with the ground. This supplemental cushioning effect is obtained due to the fact that the projection engages the surface being walked upon in advance of the engagement of the entire bottom surface. A certain amount of the jar of the step is taken up by the projection, and transmitted therethrough to the thin wall which is permitted to flex or give due to its spacing from the leather lift.

It is an object and purpose of my present invention to provide such a rubber heel lift for shoes having certain novel features of construction affording a maximum holding engagement with the ground surface to prevent slipping and also operating to produce uniform wear of the tread face of the heel lift around the marginal edge thereof.

More particularly, in one embodiment of the invention I provide the tread face of the heel lift with a cavity therein acting to pro-

duce a partial vacuum upon compression of the lift, an integral part of the lift projecting from the wall of said cavity beyond the tread face of the heel and spaced from the perimeter of the cavity, said part adapted to flex relative to the body of the heel structure and to thereby loosen or dislodge dirt or snow collecting in said cavity, upon the return of the heel structure to its normal condition.

It is a further object of my invention to provide a rubber lift for shoe heels having the above noted advantageous features, which is simple and inexpensive in its construction and capable of comparatively long and efficient service.

With the above and other objects in view, the invention consists in the improved rubber shoe heel lift, and in the form, construction and relative arrangement of its several parts as will be hereinafter more fully described, illustrated in the accompanying drawings, and subsequently incorporated in the subjoined claims.

In the drawings, wherein I have disclosed several simple and practical embodiments of the invention, and in which similar reference characters designate corresponding parts throughout the several views,—

Figure 1 is a bottom plan view of my improved heel lift;

Fig. 2 is a sectional view on an enlarged scale taken substantially on the line 2—2 of Fig. 1;

Fig. 3 is a view similar to Fig. 2 showing the condition of the heel lift when placed so under compression;

Fig. 4 is a fragmentary plan view similar to Fig. 1 showing a slightly modified form of the device, and

Fig. 5 is a detail sectional view taken on the line 5—5 of Fig. 4.

Referring in detail to the drawings, 5 designates the heel lift which is of the conventional outline form or shape, and is formed in a suitable mold from rubber or other re-

silient composition material. The upper face of this rubber heel lift which is opposed to the leather heel of the shoe is slightly dished in the usual manner and provided at the side 5 and rear margins thereof with the inclined rand surface indicated at 6, which it is noted, is effective to maintain the lift surface of the heel enclosed thereby in spaced relation to the leather lift.

10 The tread face 7 of the heel lift is provided substantially centrally thereof with a cavity 8. As shown in Figs. 1, 2 and 3, this cavity is of circular form and the wall thereof describes a single continuous arc on every line 15 of cross section. Surrounding the cavity 8, the body of the heel lift is provided with the spaced bores indicated at 9 to receive the attaching nails and washers, and each of these bores at the tread surface 7 of the heel 20 is surrounded by an annular protuberance or rib 10.

A part 11 of the heel structure is integrally formed with the wall of the cavity 8 and in the normal condition of the heel, as seen in Fig. 2, protrudes or extends beyond the tread surface 7 thereof and also slightly beyond the plane of the ribs 10. This part 11 preferably includes a plurality of spaced portions 12 which are also spaced from the perimeter of the cavity 8 and are capable of a certain relative flexing movement with respect to each other and also in relation to the wall of the cavity.

The heel lift as above described, is attached 35 to the leather shoe heel in the usual manner, and when subjected to compression under the weight of the wearer by contact with the ground surface, the central part 11 obviously is first subjected to the full effects of the load 40 pressure, thereby flexing and compressing the relatively thin central part of the rubber structure of the heel as indicated at 13 which is accompanied by a disposition of the extremity of the part 11 with the bottom surface as 45 defined by the bead 9 and a drawing of the walls of the cavity 8 around the part 11 inwardly towards the center of the lift, as will be readily seen from a comparison of Figs. 2 and 3 of the drawings. In this compression 50 and distortion of the central part of the heel lift having the cavity 8 and the part 12, a partial vacuum will be produced in said cavity, which in addition to the frictional contact of the part 11 with the ground, effectually prevents slipping. This localization of the forces 55 of compression at the inner central part of the heel lift results in a desirable balancing effect, and produces substantially uniform contact of the marginal portion of the tread 60 face 7 of the heel with the ground surface so that uniformity of wear of this part of the heel will result.

One of the more important results is the cushioning action of this part 11 which first 65 engages the surface being walked upon. The

full jar or shock of the step is received by this part 11 and, in addition to being partially taken up therein, a large portion of the shock is transmitted through this part to the thin wall of the bottom of the cavity, which is adapted to be distorted by these stresses. It is evident, therefore, that much of the jar is taken up prior to the engagement of the bottom face of the heel, as defined by beads 9, with the ground and after such engagement, 70 the rubber heel functions in the usual well-known manner to absorb the remainder of the jar or shock.

In Figs. 4 and 5 of the drawings, I have shown a slightly modified form of the device, 80 in which the side or lateral walls of the cavity 8' substantially follow the contour of the part 11 and are disposed in spaced parallel relation to the several spaced portions 12 of said part. In both embodiments of the device, I have 85 elected to form the part 11 substantially in the shape of the letter K. This however, is not essential, and the said part may be of various other shapes or forms which will produce the desirable functional results above 90 referred to.

From the foregoing description considered in connection with the accompanying drawings, the construction, manner of use and several advantages of my present invention 95 will be clearly and fully understood. It will be seen that by a very simple addition to the conventional rubber heel lift, I have materially enhanced the serviceability of such devices, increasing to an appreciable extent the period 100 of useful service without replacement, and obtaining a more evenly balanced cushioning effect with increased assurance against slipping on icy or other treacherous surfaces. I have disclosed several desirable and practical 105 structures whereby these several advantages may be obtained, but it will be understood that the essential features of my present invention may also be incorporated in various other alternative structural forms, and I 110 therefore, reserve the privilege of resorting to all such legitimate changes therein as may be fairly embodied within the spirit and scope of the invention as claimed.

I claim:

1. A shoe heel lift comprising a body of resilient compressible material having a group of protuberances on its tread face arranged in spaced relation to the marginal edges of the lift and said tread face being further provided within said group of protuberances with a cavity, and an integrally formed part projecting from the surface of said cavity in spaced relation to the perimeter thereof at the tread face of the lift and normally extending from the open side of said cavity and beyond said protuberances.

2. A shoe heel lift comprising a body of resilient compressible material having a semi-spherical cavity centrally formed in its tread

face and of a maximum depth exceeding one-half of the thickness of the lift, and a plurality of angularly related parts integrally formed with the concave wall of said cavity and directly integrally connected with each other at the center of the cavity, said parts at their free ends terminating in spaced relation to the perimeter of said cavity and normally projecting beyond the tread face of the lift whereby said parts may flex relative to each other under impact pressure.

In testimony that I claim the foregoing as my invention, I have signed my name hereto.

BENJ. W. KLEIN.
